FOREIGN PATENT DOCUMENTS

CN 306971705 * 11/2021

Primary Examiner — Elizabeth A. Albert(74) *Attorney, Agent, or Firm* — Birch, Stewart, Kolasch & Birch, LLP(57) **CLAIM**

The ornamental design for a pod for plant cultivator, as shown and described.

DESCRIPTION

FIG. 1 is a front perspective view of the pod for plant cultivator showing our new design;

FIG. 2 is a front view thereof;

FIG. 3 is a back view thereof;

FIG. 4 is a left side view thereof where the right side view is a mirror image;

FIG. 5 is a top plan view thereof; and,

FIG. 6 is a bottom plan view thereof.
